UNITED STATES PATENT OFFICE.

WILLIAM P. WARREN, OF SHERIDAN, ILLINOIS.

WHEELED SCRAPER.

No. 821,560.

Specification of Letters Patent.

Patented May 22, 1906.

Application filed February 5, 1906. Serial No. 299,628.

To all whom it may concern:

Be it known that I, WILLIAM P. WARREN, a citizen of the United States, residing at Sheridan, in the county of Lasalle and State 5 of Illinois, have invented certain new and useful Improvements in Wheeled Scrapers; and I do declare the following to be a full, clear, and exact description of the invention, such as will enable others skilled in the art to 10 to which it appertains to make and use the same.

My invention relates to improvements in attachments for wheeled road-scrapers, and more particularly to the one set forth in Letters Patent No. 661,094, granted to me November 6, 1900.

The object of the invention is to provide a simple and efficient scraper-blade attachment of this character which may be readily 20 applied to the scraper and adjusted so that it may be effectively used for repairing roads and for other purposes.

With the above and other objects in view the invention consists of certain novel features of construction, combination, and arrangement of parts, as will be hereinafter 25 described and claimed.

In the accompanying drawings, Figure 1 is a plan view of my improved attachment applied to a wheeled scraper. Fig. 2 is a side elevation of the same, and Fig. 3 is a longitudinal sectional view.

Referring more particularly to the drawings, A represents the carrying-wheels of the 35 scraper, which are journaled upon the ends of a transverse axle B, which has secured upon it crank-arms c. The scoop D is suspended from the axle and consists of the sides F, a scraper-blade G, which is hinged at its upper 40 rear ends to said sides, as at g, the draft-frame K, and the curved links I, which latter have their lower ends pivotally connected to the upturned ends of the blade G. The draft-frame K comprises the angle metal bars 45 or straps L, M, and K' and has attached to it the draft pole or tongue J and a rearwardly-extending beam M, upon which the seat O is secured. The scoop D is suspended by pivoted arms H and by links h, which latter 50 have their lower ends pivoted upon the sides F of the scoop and their upper ends pivoted to the cranks c on the shaft B. The links h are provided about midway their lengths with recesses h' to engage the axle when 55 raised to their highest position to assist the crank-arms in holding the scoop elevated. Upon the shaft B is secured a lever P, by means of which the scoop may be raised or lowered, as will be readily understood.

The scraper above described is the same as 60 that set forth in my patent previously referred to with the exception that the back-board of the scoop and its operating-lever are omitted. This is done when my improved attachment 1 is applied to the scraper. 65 This attachment comprises a frame 2, consisting of two pivotally-connected sections 3 4. The larger section 3 is pivotally connected to the sides F of the scoop, so that the frame may swing in a vertical plane, and the 70 smaller section 4, which carries a scraper-blade 5, is pivotally connected to the section 3, so that the blade may be adjusted angularly in a horizontal plane. The frame 3 preferably consists of a strap or bar of metal 75 6, bent in semicircular form and having its ends pivoted upon the sides F of the scoop, as shown at 7. These ends are connected by a cross-bar 8, which has secured between it and a clamp-plate 9 upon its upper face one 80 end of a centrally-disposed longitudinal bar 10. The latter has secured upon the upper face of its rear end a clamping bar or plate 11. The rear ends of the plates or bars 10 11 85 are spaced apart to receive the semicircular bar 6, as shown in Fig. 3, and between the intermediate portions of said bars is slidably and adjustably mounted the semicircular bar or plate 12 of the horizontally-swinging frame-section 4. The ends of the bar 12 extend 90 rearwardly and are connected by a cross-bar 13, which is pivoted at its center, as shown at 14, to the bars 10 11. The extreme rear ends of the semicircular bar 12 are bent downwardly, as at 16, and have secured 95 to their inner faces the scraper-blade 5, which latter may be of any desired form and construction. The blade may be secured in an angular position by any suitable means; but I preferably form in the central portion of 100 the curved bar 12 a series of apertures 17, through which and through openings in the bars 10 11 may be passed a pin or the like 15. When this attachment is applied to the scraper, as shown, and the latter is drawn forwardly, the earth cut by the scraper G passes over the same and is collected by the scraper-blade 5 of the attachment. By adjusting the latter angularly the earth may be discharged upon either side of the machine and 110

as rapidly as desired. This attachment renders the machine well adapted for repairing roads and for similar purposes.

From the foregoing description, taken in connection with the accompanying drawings, the construction and operation of the invention will be readily understood without requiring a more extended explanation.

Various changes in the form, proportion, 10 and the minor details of construction may be resorted to without departing from the principle or sacrificing any of the advantages of this invention as defined by the appended claims.

Having thus described my invention, what 15 I claim as new, and desire to secure by Letters Patent, is—

1. An attachment for scrapers comprising a vertically-swinging frame, a horizontally-swinging frame pivotally attached thereto, a blade carried by said horizontally-swinging frame, and means for securing said horizontally-swinging frame in an adjusted position.

2. An attachment for scrapers comprising 25 a vertically-swinging frame, a horizontally-swinging frame consisting of a semicircular bar having downturned ends and a cross-bar, said cross-bar being pivoted at its center to

said vertically-swinging frame, a scraper-blade upon the depending ends of said semicircular bar, and means for adjustably connecting said semicircular bar to said vertically-swinging frame.

3. An attachment for scrapers comprising a vertically-swinging frame consisting of a 35 semicircular bar having pivot-openings at its forwardly-projecting ends, a cross-bar and a longitudinal bar, a horizontally - swinging frame consisting of a semicircular bar having rearwardly-projecting downturned ends, and a cross-bar connecting said ends, the last-mentioned cross-bar being pivoted upon said longitudinal bar, the scraper-blade being secured to said depending ends, and a pin passed through alining openings is said longitudinal bar and in the semicircular bar of 40 said horizontally - swinging frame, substantially as described and for the purpose set forth.

In testimony whereof I have hereunto set 50 my hand in presence of two subscribing witnesses.

WILLIAM P. WARREN.
